RAILROAD-SWITCH.

1,138,606.

Specification of Letters Patent.

Patented May 4, 1915.

Application filed March 26, 1913. Serial No. 756,868.

To all whom it may concern:

Be it known that I, IR A. CALL, a citizen of the United States, residing at Denver, in the county of Denver and State of Colorado, have invented new and useful Improvements 5 in Railroad-Switches, of which the following is a full, clear, concise, and exact description, reference being had to the accompanying drawing, forming a part of this 10 specification.

My invention pertains to railroad switches, and particularly relates to switches of the type known as "stub switches," *i. e.*, switches in which lengths of rail are movably mounted between the approaching and the trailing side of the switch, such rail lengths being adapted to form continuations of the fixed rails, and to make connection between the main rails on the approaching side of the 15 switch, and either of the main rails or the siding rails on the trailing side of the switch, according as they are moved into one position or the other. Stub switches have the advantage over the switches now generally in use (known as split-point switches) 20 in that they are not liable to become clogged, as split-point switches are; and that they are not open to the objection, frequently urged against split-point switches, that the extreme end of the switch rail is very readily broken. Stub switches, in the forms in which they have been produced until quite lately, have been subject, however, to important and very dangerous disadvantages 25 of their own. Among these disadvantages may be mentioned the objection that the heavy strains and impacts imparted by the cars to the switch, have in the course of the wear of the switch, resulted in the stub rails failing to make perfect alinement between 30 the rails on the approaching and trailing sides of the switch. This failure to make proper alinement, or "lapping" as it is technically called, has resulted in serious disadvantages, and has been one of the causes of the 35 stub switch being considered unsafe and impracticable. With these conditions in view, I have heretofore devised several forms of stub switches which avoid the disadvantages of the older forms of stub switches; and it is an object of the present invention 40 to produce another form of stub switch, which will be safe in use under the severest conditions of wear, etc., which will not be 45 subject to impairment by reason of tempera-

ture changes or the creeping of the rails, which will be capable of withstanding the shocks and strains imparted to it by the cars, and which will be of a simple and durable construction.

A stub switch constructed in accordance with my present invention is described, by way of example, in the following specification and shown in the accompanying drawings. It is to be understood, however, that the form described and shown is not the only one in which my invention may be embodied, and that changes may be made in the construction which is described and shown without exceeding the scope of my invention as defined in the appended claims.

In the drawings:—Figure 1 is a plan of stub switch constructed in accordance with my invention; Fig. 2 is a section through the same, the section being taken on the line 2—2 of Fig. 1, looking in the direction of the arrows; Fig. 3 is a sectional view, on an enlarged scale, of an end of one of the fixed rails, and the guard rails adjacent thereto, showing the manner employed for securing the fixed rails to the bed plates of the switch; Fig. 4 is a sectional view, on an enlarged scale, through the movable end of one of the pairs of stub rails, showing the manner of limiting the movements of said pair of stub rails; Fig. 5 is a perspective view of the block employed for connecting the rails of each pair of stub rails together; Fig. 6 is a sectional view through the pivoted end of one of the pairs of stub rails; 50 and Fig. 7 is a longitudinal sectional view taken on the line 7—7 of Fig. 1 looking in the direction of the arrows.

Like reference characters refer to like parts throughout the specification and the several figures of the accompanying drawings.

Referring now to the drawings, and particularly to Fig. 1 thereof, 10 and 10^a indicate the fixed main line rails, on the approaching end of the switch, and 11 and 11^a indicate the fixed main line rails on the trailing end of the switch. 12 and 12^a indicate the siding rails on the trailing side of the switch. Throughout the following specification, the side of the switch which includes the rails 10, 11 and 12 will be referred to as the "main line" side of the switch, and the side of the switch which includes the rails 10^a, 11^a and 12^a will be referred to as the 100 105 110

"turn out" side of the switch. 13 and 13^a indicate fixed guard rails which are provided, adjacent the main line rails, on the approaching end of the switch.

5 The fixed rails are rigidly secured to bed plates 14 and 14^a, provided at the main line and turn out sides of the switch, respectively. It will be seen that the fixed rails are in pairs at each side, and at each end of 10 the switch; and these pairs of fixed rails are preferably secured to the bed plates 14 and 14^a in the same manner. It will be sufficient therefore, to describe the manner of securing one pair—say the main line rail 10 and 15 guard rail 13—to the bed plate. Referring, therefore, to Fig. 3, which is a section through the rails 10 and 13, 15 indicates angle irons, which are secured to the bed plate 14 by means of bolts 16 or the like, and which are secured to the rails 10 and 13 by means of bolts 17 passing through these rails, and through a spacing block 18 which is interposed between them. The block 18 is shaped so as to conform to the adjacent 20 inner surfaces of the rails, and is hollowed out, at its upper part, so as to allow sufficient room for the flanges of the car wheels. It will be seen that by this means a firm and rigid connection is made between the rails 30 10 and 13 and the bed plate 14. It will also be seen that the only operation necessary to be performed in the field is the boring of the webs of the rails 10 and 13 to receive the bolts 17. The other parts will be supplied 35 ready for fitting, and can readily be assembled at the place where the switch is to be installed.

Secured upon the bed plates 14 and 14^a, 40 are spacing plates 19 and 19^a of such length that their ends will abut against the ends of the fixed rails at the approaching and trailing ends of the switch. This abutting relation is clearly shown in Fig. 7, similar sections at the other points of abutment being identical. These spacing plates 19 and 19^a serve 45 to maintain definitely the spaced relation between the ends of the fixed rails, which relation, without the provision of the spacing plate, would be liable to vary by reason of the contraction and expansion of the fixed rails owing to temperature changes, or by reason of the creeping of the fixed rails. Upon the spacing plates 19 and 19^a are mounted stub rails 20, 20^a, 21 and 21^a of 50 the switch, which are arranged in two pairs, of which pair the pair 20 and 21 is pivotally mounted upon the spacing plate 19, and the pair 20^a and 21^a is pivotally mounted upon the spacing plate 19^a. The stub rail 20 is 55 adapted to make connection between the approaching main line rail 10 and either the trailing main line rail 11 or the siding rail 12, according to the position of the stub rails. The stub rail 21 acts as a guard rail for the 60 stub rail 20. The stub rail 20^a is adapted to

make connection between the approaching main line rail 10^a and the trailing main line rail 11^a, when the stub rails are in one position. The stub rail 21^a is adapted to make 70 connection between the approaching main line rail 10^a and the siding rail 12^a when the stub rails are in the other position. When the switch is in siding position, the stub rail 20^a forms a guide rail for the stub rail 21^a. 75

The stub rails 20^a and 21^a are connected together, at the trailing end of the switch, by means of bolts 22 (Fig. 6) passing through them and through a block 23, which block is of a generally similar character to the blocks 18 described above. The block 23 is, however, provided with a downwardly extending threaded pin 24, which passes through alined holes in the spacing plate 19^a and bed plate 14^a, and is tightened to an extent sufficient to maintain the stub rails firmly in position while permitting them to move about the pin 24 as a pivot. When the nut 25 has been properly placed upon the pin 24, it is preferably secured in position by means of a split pin 26. By this means the stub rails 20 and 20^a are pivotally mounted upon the spacing plate 19^a, so as to be able to swing about the pin 24 so as to bring the rail 20^a, or the rail 21^a, into alignment with the main line rail 10^a, according 80 as it is desired that the train pass into the siding or continue on the main line. The stub rails 20 and 21 are pivoted upon the spacing plate 19 in the same manner, and preferably by the same means as that described with reference to the rails 20^a and 21^a. They are pivoted, however, at the approaching side of the switch, instead of at the trailing side of the switch. 85

The stub rails 20^a and 21^a are connected, at 90 the ends thereof adjacent the approaching end of the switch, by means of bolts 27 passing through their webs, and through a connecting block 28 of a similar nature to the block 23 described above. The block 28 is provided with a downwardly extending threaded pin 29, which passes through slots 30 and 31 formed in the spacing plate 19^a and the bed plate 14^a, respectively. A nut 32 is screwed upon the pin 29, beneath the bed plate 14^a and is secured in its proper position by means of a split pin 33, all in a similar manner to that described with reference to the block 23 and nut 25. The slots 100 30 and 31 are so positioned and are of such length that their ends form stops for limiting the movement of the stub rails 20^a and 21^a. When the pin 29 abuts against the left hand ends of the slots 30 and 31 (Fig. 4), the stub rail 20^a is in accurate alinement with the main line rail 10^a, and when the pin 29 is in engagement with the right hand ends of the slots 30 and 31, the stub rail 21^a will 105 be in accurate alinement with the main line rail 10^a. The stub rails 20 and 21 are con- 110

nected, at the ends thereof adjacent the trailing end of the switch in the same manner as that in which the ends of the stub rails 20^a and 21^a adjacent the approaching end of the 5 switch are connected. The bed plate 14 has extending therefrom, adjacent the center of the inner side thereof, a lug 34. A walking beam 35 is pivoted, intermediate its ends, upon the lug 34, and is connected, by means 10 of a pivoted link 36, to a bracket 37 which is attached to the inner side of the stub rail 21 adjacent the trailing end of the switch. The opposite end of the walking beam 35 is connected, by means of a pivoted link 38, with 15 an ear 39, which extends from the inner side of the stub rail 20^a, at the approaching end of the switch. It will be seen that the connection, established by the walking beam 35 and the links 36 and 38, between the pair of 20 stub rails 20 and 21, and the pair 20^a and 21^a, is such that a movement of the ends of the stub rails 20 and 21 toward the turn out side of the switch, will necessarily result in a movement of the stub rails 20^a and 21^a to 25 toward the main line side of the switch. In other words, supposing the stub rails to be in the position shown in Fig. 1; *i. e.*, in the position in which the stub rails 20 and 20^a make connection between the approaching 30 main line rails 10 and 10^a and the trailing main line rails 11 and 11^a: if the stub rails 20 and 21 are moved toward the turn out side of the switch, thus bringing the trailing end of the stub rail 20 into alinement with 35 the siding rail, a corresponding movement of the stub rails 20^a and 21^a will be effected, thus bringing the stub rail 21^a, in place of the stub rail 20^a, into alinement with the main line rail 10^a. It will thus be seen that 40 the rail 20 is always in use, carrying the cars along the main line or into the siding, according as its trailing end is in alinement with the trailing main line rail 11, or the siding rail 12. On the other hand, the rail 45 20^a only carries the cars when the switch is in main line position; and the rail 21^a only carries the cars when the switch is in siding position.

In order to effect the movement of the stub 50 rails from one position to the other, I provide a stub shaft 40, which is rockably mounted in a bearing 41 secured to the extended end 42 of one of the track ties. The stub shaft 40 is provided, at one of its ends, 55 with a crank 43 which is connected by means of a link 44 with an ear 45, which extends over the stub rail 20, at a point adjacent the trailing end thereof. To the opposite end of the stub shaft 40 is connected an operating 60 lever 46. It will be seen that, by rocking the crank 43 by the use of the lever 46, the stub rails will be caused to move from the position shown in Fig. 1, to that in which the stub rail 20 makes connection between the 65 main line rail 10 and the siding rail 12, and

the stub rail 21^a makes connection between the main line rail 10^a and the siding rail 12^a.

In order to support the bed plates 14 and 14^a at the points of junction between the fixed rails and the stub rails, I may provide 70 auxiliary supports at these points. In the construction shown in the drawings, these supports are shown as being inverted short lengths of rail 47 (Figs. 4 and 6) secured to each side of the bed plate 14^a by means of 75 rivets 48.

The construction described above produces a stub switch which is absolutely safe even under the severest conditions of wear. Lipping of the rails is impossible, and any 80 shocks or strains to which the switch may be subjected by passing cars are adequately provided for. Vertical movement of the stub rails is effectually prevented by the nuts 25—25 and 32—32 on the ends of the pins 85 24—24 and 29—29, respectively. The switch is of a simple and durable construction and may be installed with ease and with a minimum of work in the field.

Having thus described my invention, 90 what I claim as new and desire to secure by Letters Patent is—

1. A railroad track switch of the butt-end type, comprising approaching and trailing track rails, throw rails between the ends 95 of said track rails operating from their opposite ends, and bed plates having their ends abutting against the ends of the track rails and forming rigid connections between said approaching and trailing track rails 100 and over which said throw rails operate.

2. In a railroad switch, the combination with approaching main line rails, trailing main line rails and siding rails, of bed plates having their ends abutting against the ends 105 of said rails, a stub rail located between the approaching and trailing rails on the main line side of the switch and pivoted on one of said bed plates adjacent the approaching end of the switch, the other end of said stub rail being movable so as to aline either with the trailing main line rail or the siding rail, a pair of stub rails disposed side by side at the turn out side of the switch and pivoted 110 on one of said plates adjacent the trailing end of the switch, one stub rail of said pair being in alinement with the trailing main line rail and the other stub rail of said pair being in alinement with the siding rail, said pair of stub rails being movable so as to 115 bring one or the other of them into alinement with the approaching main line rail, and suitable means for shifting said stub rails to change the switch from main line to siding position and vice versa. 120

3. In a railroad switch, the combination with approaching main line rails, trailing main line rails and siding rails, of bed plates having their ends abutting against the ends of said rails, a stub rail located be- 130

tween the approaching and trailing rails on the main line side of the switch and pivoted to one of said bed plates adjacent the approaching end of the switch, the other end 5 of said stub rail being movable so as to aline either with the trailing main line rail or the siding rail, a guard at the side of said stub rail and moving therewith, a pair of stub rails disposed side by side at the turn 10 out side of the switch and pivoted adjacent the trailing end of the switch, one stub rail of said pair being in alinement with the trailing main line rail and the other stub rail of said pair being in alinement with the 15 siding rail, said pair of stub rails being movable so as to bring one or the other of them into alinement with the approaching main line rail, and connections whereby when one of said stub rails is moved the 20 other stub rails participate in such movement.

4. In a railroad switch, the combination with a pair of bed plates, approaching main line rails rigidly secured to said bed plates, 25 trailing main line rails rigidly secured to said bed plates, and siding rails rigidly secured to said bed plates, said rails having

their ends abutting against the ends of said bed plates, of a stud rail located between the approaching and trailing rails on the 30 main line side of the switch and pivoted adjacent the approaching end of the switch, the other end of said stub rail being movable so as to aline either with the trailing main line rail or the siding rail, a pair of stud 35 rails disposed side by side at the turn out side of the switch and pivoted adjacent the trailing end of the switch, one stub rail of said pair being in alinement with the trailing main line rail and the other stub rail of 40 said pair being in alinement with the siding rail, said pair of stud rails being movable so as to bring one or the other of them into alinement with the approaching main line rail, and means for shifting said stub rails 45 to change the switch from main line to siding position and vice versa.

In witness whereof, I have hereunto subscribed my name in the presence of two witnesses.

IRA A. CALL.
